Mary D. Powers
Cloud M. Chapman.

UNITED STATES PATENT OFFICE.

FRANK T. POWERS, OF DOUGLASTON, NEW YORK.

APPARATUS FOR DRYING PLATES OF VARIOUS SORTS.

Application filed June 29, 1922. Serial No. 571,839.

To all whom it may concern:

Be it known that I, FRANK T. POWERS, a citizen of the United States, and resident of Douglaston, in the county of Queens and 5 State of New York, have invented certain new and useful Improvements in Apparatus for Drying Plates of Various Sorts, of which the following is a specification.

My invention relates to apparatus for drying plates or sheets of metal, glass or other material and more particularly to the metal plates used as printing plates in the photo-mechanical reproduction art. It is intended 10 for use in the processes in which metal plates are employed and which at certain stages in the process require drying.

The object of the invention is to furnish a quick, easy, sure, safe means for drying plates of this character after they have been 20 washed or rinsed with water. The method generally employed heretofore consists in applying to the surface of the plate by hand a mop of damp chamois skin. By gently patting the plate with the damp leather the 25 drops of water are absorbed, and after this operation is carefully carried out the plate is ready for final drying by heating it over a gas flame.

The disadvantages of this method are both 30 numerous and obvious. The time required is considerable, the possibilities of incomplete drying due to carelessness of the operator are ever present and the damage and loss ensuing in the event of improper or incomplete drying are quite material. The 35 last of the moisture must then be removed by heating the plate over a gas flame or by equivalent means.

By the use of my invention these disadvantages of the present method are overcome. The wet plate is placed between two 40 water absorbent surfaces and a high pressure is applied to the two surfaces of the plate simultaneously. The absorbent surfaces are heated so that in a brief interval 45 the wet plate is both dried and warmed ready for the next operation. The action is quick, positive and uniform. Every plate receives the same treatment as every other 50 plate, which is conducive to uniformity of product. Other advantages and special features of the invention will be apparent from the ensuing description to one familiar with the art.

55 In the accompanying drawing is shown a perspective of one of the preferred embodi-

ments of the invention. Referring in detail to the numbered parts of the preferred form of embodiment shown in the drawing: 1 is a frame or stand, preferably of cast iron 60 carrying a rigidly attached stationary platten 2 having within it cellular or tubular passages for the circulation of steam or hot liquid. Pipe connections 3, 3, furnish means for supplying steam or heated liquid from 65 any suitable source.

To the under surface of said platten is affixed a layer of water absorbent material 3^a. A second cellular or tubulated platten 4 is arranged under first mentioned platten 70 2, so as to move vertically in guides 5, 5. This platten also is provided with internal cellular or tubular passages for the circulation of a heating medium, similar to platten 2.

Attached to the upper surface of platten 4 is a water absorbent layer of material 6. The lower platten 4 is movable by means of the links 7, 7, pivoted to the lever arms 8, 8, attached to shaft 9, to which is attached the 80 hand lever 10. By means of the toggle system composed of hand lever 10, shaft 9, lever arms 8, 8, and links 7, 7, the platten 4 may be moved upwardly into forcible contact with platten 2, or moved downwardly away 85 from it.

With the hand lever 10 in one extreme position there will be a space between the upper and lower plattens, while with the hand lever 10 at its other extreme position 90 the two plattens will be tightly pressed together.

It is obvious that many other methods of construction and other arrangements of parts will give similar results in operation. The 95 plattens between which the plate is dried may be in a vertical, inclined, or horizontal position without affecting the result. When the plattens are placed in an inclined or a vertical position it is particularly easy to 100 heat them by passing a current of hot air between them. This may be accomplished with a gas burner or other source of heat so disposed that the heat passes upwardly between the two plattens when in their open 105 position.

Having described the mechanism of the preferred embodiment of my invention, I will now outline its method of operation.

The hand lever 10 is placed in a position 110 which corresponds to the open position of the two plattens 2 and 4. The plate to be

dried is inserted face up between the two plattens and rested on the absorbent covering of the lower platten 4. The hand lever 10 is then manually moved to its other extreme position which forcibly presses the plate up against the absorbent surface of the upper platten 2.

The toggle form of the lever mechanism shown enables the operator to exert a very high final pressure upon the plate with moderate pressure on the hand lever. After a brief interval the hand lever 10 is returned to its first or starting position and the plate, now dried, is removed from the lower platten 4, and is ready for the next operation.

Having described my invention and its method of operation, I will now state what I claim to be novel and new and upon which I desire to secure Letters Patent:

20 1. In an apparatus for the drying of

photo-mechanical printing plates, the combination of two absorbent surfaces with means for pressing said surfaces against opposite sides of said plates.

2. A device for drying photo-mechanical printing plates comprising in combination two plattens having water absorbent surfaces, means for heating said surfaces by the circulation of a heated fluid and means for pressing the said plates between the 25 30 said surfaces.

3. A device for drying photo-mechanical printing plates comprising in combination two heated absorbent surfaces and means for simultaneously pressing said heated surfaces 35 against opposite sides of said plates.

Signed at New York, in the county of New York and State of New York, this 20th day of May, A. D. 1922.

FRANK T. POWERS.
